UNITED STATES PATENT OFFICE.

ALBERT LATHAM, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

1,342,120.

Specification of Letters Patent.

Patented June 1, 1920.

Application filed February 12, 1918. Serial No. 216,735.

To all whom it may concern:

Be it known that I, ALBERT LATHAM, a citizen of the United States, residing at Beverly, in the county of Essex and State of Massachusetts, have invented certain new and useful Improvements in Skiving-Machines; and I do hereby declare the following to be a full, clear, and exact description of the invention, such as will enable others skilled in the art to which it appertains to make and use the same.

The present invention relates to skiving machines and more particularly to the knives and coöperating mechanism employed in such machines.

The invention is more particularly applied to tubular skiving knives of the type in which a thin flexible knife blade is rigidly clamped to a blade holder. The knives are rotated at high speed and it is essential that the knife edge shall not deviate in the slightest degree from the true circle of rotation of the knife. In order to secure this result the knife blade must be rigidly clamped to a holder having a true blade engaging surface and the supporting shaft upon which the holder is mounted must be accurately supported in order that it shall permit a free rotation of the shaft without whipping or vibrating it.

One object of the present invention, therefore, is to reorganize and improve the construction of skiving knives of this type in order that all portions of the cutting edge of the knife shall be concentric with the axis of rotation.

A further object of the invention is to improve the mechanism for clamping the knife blade to the holder and adjusting the knife blade relative to the holder in such a manner that these operations are greatly facilitated and the liability of injury to the operator is eliminated.

With these objects in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a longitudinal section in

elevation of the skiving knife and coöperating parts; Fig. 2 is a detail illustrating a portion of the front of the knife with certain parts in section; Fig. 3 is a detail of one of the spacing members; and Fig. 4 is a detail illustrating a section of the mechanism at the rear end of the knife shaft for adjusting and clamping the knife.

The knife shown in the illustrated embodiment of the invention comprises a thin flexible blade 10 adapted to be clamped within a blade holder 12 which has a blade engaging surface shaped to cause the knife blade to conform to a true cylinder when clamped in position. The holder is provided with a base portion 11 which is threaded upon the flange 13 formed upon the outer end of a knife shaft 17. The blade 10 is supported at its rear edge upon a carrier ring 14 which is provided with an annular groove 15 engaged by projections 16 struck up from the surface of the blade, as shown clearly in Fig. 1. The blade 10 is clamped rigidly to the holder 12 adjacent the cutting edge of the blade by a ring 18 having an inner tapered face 19 which is engaged by a clamping plate 20 when the latter is moved axially of the knife. The expansion of the ring 18 is permitted by the provision of a series of longitudinal slots 21 extending rearwardly from the edge of the ring, as shown in Fig. 1. The blade carrier 14 is traversed in and out to properly adjust the blade through a threaded connection 22 with the clamping ring 18 which is secured through fastenings 23 to the outer end of a rotary sleeve 25 received within the hollow knife shaft 17. During the rotation of the ring 18 to adjust the blade, the carrier ring 14 is prevented from rotating by engagement with the surface of the blade holder 12 and to insure that this frictional engagement shall be sufficient to retain the ring in position the latter is preferably split, as indicated at 28, and is sprung into the holder. The clamping plate 20 is secured to the outer end of a rod 30 which is splined to the hollow sleeve 25 through a transverse pin 31 having its opposite ends received in lengthwise slots 32 formed in the sleeve to permit the rod to move lengthwise of the sleeve without rotating relative thereto.

In the present invention the clamping and

adjustment of the knife blade are controlled from the opposite end of the knife shaft and in addition, provision is made for completely ejecting the several rings together 5 with the blade from within the blade holder to permit replacement of a worn blade with a new one. This mechanism provides a convenient and quick adjustment of the knife blade to the desired point and insures the 10 rigid clamping of the blade to the holder in whatever position the blade may be located. The clamping rod 30 extends within the front end of the sleeve 25 a distance sufficient to afford a proper bearing for the rod 15 and is provided at its inner end with a threaded bore 35 which receives the correspondingly threaded end of a stem 36 which extends completely through the shaft and has keyed upon its opposite end a hand 20 wheel 37. The sleeve 25, to which the adjusting ring is secured, also extends completely through the hollow knife shaft and has a hand wheel 39 secured thereto. With this construction a rotation of the hand 25 wheel 39 causes a like rotation of the ring 18 and traverses the blade in or out of the holder, whereas a rotation of the hand wheel 37 moves the rod 30 and clamping plate 20 lengthwise of the knife to expand or 30 contract the clamping ring 18. The knife blade is ejected from within the holder by moving the sleeve 25 and stem 36 lengthwise of the knife shaft and in order to permit this lengthwise movement of the members when 35 desired, and at the same time normally preserve the proper operative relation of the several parts, a spacing collar 40 is made in two parts, one of which is indicated at 41, and is interposed between the hand wheel 40 39 and a drive pulley 42 keyed to the knife shaft 17. This collar is provided with an overhanging flange 43 which receives a smaller collar 44 having an inner tapered face 45 adapted to engage with a correspondingly 45 tapered face 46 formed on an annular flange 47. The operating collar 44 has a plurality of pins 49 which pass loosely through holes formed in the hand wheel 39 into a position where their outer ends may be engaged by a 50 face of the hand wheel 37. When the hand wheel 37 is rotated in a direction to clamp the knife blade to the holder, both the clamping plate and the hand wheel are drawn toward one another. The hand wheel then 55 moves the collar 44 through the pins 49 until the tapered face 45 engages with the corresponding face of the flange 47 to clamp the two parts of the collar together. A continued rotation of the hand wheel then moves 60 the split collar into the recess 51 formed in the face of the pulley 42, clamping the knife shaft 17 and sleeve 25 together. When it is desired to remove the knife blade from the holder the hand wheel 37 is slackened off sufficiently to permit the collar 40 to be disengaged from the recess 51, after which the two parts of the collar may be separated and removed from the shaft. After the removal of the collar the hand wheels 37 and 39 may be moved bodily together with the hollow 70 sleeve 25 and adjusting rods a sufficient distance to completely expose the knife blade. It will be noted that with this construction, when the stem 36 is threaded into the rod 30 to tighten the clamp, the thrust of the stem is transmitted through the pins 49 and collar 40 to the pulley 42, which is rigidly secured to the knife shaft.

The high speed at which these knives are rotated renders it necessary to provide accurately alined bearings of ample size for the knife supporting shaft. In order to avoid the difficulty and expense incident to the formation of stationary bearings of this character, the present invention contemplates the provision of self-alining bearings which permit the shaft to be rotated at high speeds without chattering or vibrating. The knife shaft 17 is supported at opposite ends in journal boxes 60 and 61, each of which is 80 provided with a rounded annular bead 63 midway between its ends which is of slightly greater diameter than the outer diameter of the box. Each journal box is received within an opening 65 formed in the 85 frame 66 of the machine and of a size to cause the bead 63 to fit closely therein. With this construction a slight swiveling movement of the box within the opening 65 is permitted. The annular bead formed 90 upon each box is engaged by the end of a plug 67 threaded into an opening formed in the frame and having an inner cup-shaped end adapted to fit the bead. The plug is provided with a lengthwise bore 68 into the 95 lower end of which a pin 69 is forced, as shown clearly in Fig. 1. This pin has a neck 70 of reduced diameter adapted to be received within an opening 71 of slightly larger diameter formed in each box. When the 100 threaded stud 67 is loosened slightly the bearing boxes are permitted to aline themselves accurately with the shaft after which each box is rigidly secured in alined position by tightening the stud. The neck 70, 115 projecting within the opening 71, maintains the box against rotation with the shaft but as the opening is slightly larger than the neck in a direction lengthwise of the box, the necessary alining movements of the journal box are permitted. Each box is provided with lubricating grooves 73 which communicate with a duct 75 formed in the pin 69 and supplied with lubricant in any suitable manner. The knife shaft is maintained in position through the provision of an annular flange 77 and a thrust collar 78 disposed upon opposite sides of the journal box 60. The thrust collar is preferably 120 keyed to the shaft and is prevented from 130

moving longitudinally through a lock nut 79 threaded to the shaft behind the thrust collar.

While it is preferred to employ the specific construction and arrangement of parts shown and described, it will be understood that this construction and arrangement is not essential except so far as specified in the claims, and may be changed or modified 10 without departing from the broader features of the invention.

The invention having been described, what is claimed is:

1. A skiving machine comprising a hollow knife shaft, a holder secured to one end of the shaft, a knife blade, and means for clamping the blade to the holder including a clamping disk, a stem secured to the disk and projecting into the front end of the 20 knife shaft, an operating rod threadedly connected to the stem and projecting through the knife shaft to the rear end, means for rotating the knife shaft, and an actuating member secured to the rear end of 25 the rod for rotating the latter.

2. A skiving machine comprising a knife holder, a clamping ring having an inner tapered face, a blade carrier threadedly connected to the periphery of the clamping 30 ring, a knife blade secured to the carrier, a clamping disk having a tapered face corresponding to the tapered face upon the clamping ring, and means for moving the disk axially of the ring to clamp the blade 35 to the holder.

3. A skiving machine comprising a hollow knife shaft, a knife holder secured to one end of the shaft, a knife blade, a drive pulley secured to the opposite end of the shaft, a 40 blade adjusting rod and a blade clamping rod received within the knife shaft and projecting from the rear end, a clamping ring and a clamping disk secured to the outer ends of the rods, an actuating member secured to the rear end of each rod to rotate the rod, and detachable connections for normally preventing outward movement of the two rods to maintain the clamping ring and disk within the holder.

50 4. A skiving machine comprising a hollow knife shaft, a drive pulley secured to the knife shaft, an operating rod received within the knife shaft, a hand wheel secured to the rod, and a detachable collar interposed

between the hand wheel and pulley to normally maintain a predetermined spaced relation between the two.

5. A skiving machine comprising a hollow knife shaft, an operating rod received within the knife shaft, and detachable means 60 for clamping the rod and shaft together designed to permit a relative axial movement of the two when removed.

6. A skiving machine comprising a hollow shaft, an operating rod received within 65 the shaft, a collar formed in halves surrounding the rod, means for actuating the collar to clamp the rod and shaft together, and means for retaining the two halves of the collar in assembled relation when the rod 70 and shaft are so locked together.

7. A skiving machine comprising a knife shaft, a rod received therein and projecting from one end, a spacing collar including 75 two separable halves, and means for actuating the collar to lock the shaft and rod together and to preserve a predetermined axial relation between the two designed to prevent removal of the collar when in clamping position.

8. A skiving machine comprising a hollow knife shaft, a knife holder secured to one end of the shaft, a knife blade, means for adjusting the blade relative to the holder, means for clamping the blade to the 85 holder, an adjusting rod and a clamping rod extending through the knife shaft, means for actuating the rods to operate the clamping and adjusting mechanisms, and detachable means for permitting the complete 90 ejection from the knife holder of the knife blade together with the clamping and adjusting mechanisms.

9. A skiving machine comprising a hollow knife shaft, a knife holder secured to one 95 end of the shaft, a knife blade, means for clamping the knife blade to the holder, a clamping rod extending through the shaft and threadedly connected with the clamping means, an actuating member secured to the 100 opposite end of the rod and a spacing collar interposed between the actuating member and the end of the knife shaft and through which the thrust of the rod is transmitted when actuated to move the clamping member inwardly to clamping position.

ALBERT LATHAM.
